UNITED STATES PATENT OFFICE.

JOHN T. MCENNANEY, OF ATLANTA, GEORGIA, ASSIGNOR TO WILLIAM R. CHRISTIAN, OF MILAN, TENNESSEE.

TIRE-TIGHTENER.

SPECIFICATION forming part of Letters Patent No. 253,935, dated February 21, 1882.

Application filed October 6, 1881. (No model.)

To all whom it may concern:

Be it known that I, JOHN T. MCENNANEY, of Atlanta, in the county of Fulton and State of Georgia, have invented a new and useful Improvement in Spoke and Tire Tighteners, which improvement is fully set forth in the following specification and accompanying drawings, in which—

Figure 1 is a perspective elevation of the spoke and tire tightener attached to the section of a wheel, and Fig. 2 is a top view of the clamp.

The object of my invention is to provide a spoke and tire tightener, and it belongs to that class in which the felly is expanded and the individual spokes are forced into the hub, as will be hereinafter more fully shown.

In the accompanying drawings, A represents the felly, and B the spoke. Encircling the spoke is a clamp formed of two semicircular parts, C C'. These are hinged together at one end at D, and at the opposite end the part C is provided with a threaded bolt, E, carrying a nut. This bolt is hinged at F to the part C, and when desired for clamping purposes the nut on the end of this bolt is swung into position and screwed up against the projecting end of the part C'. The ends of the circular clamp C' are each provided in their upper face with sockets G, in which are loosely placed the lower ends of the legs I, that project from the cross-frame H, resting on the felly.

J represents a cross-bar, through which centrally passes the screw-threaded bolt N, having a nut, O, at its upper end. The lower end of this bolt rests in a socket in the cross-frame H. At each end of the cross-bar J is an arm, K, having a hook, M, at the lower end, on which the felly A rests. The upper end of this arm

is screw-threaded, L, and passes through a 40 screw-threaded aperture in the end of the cross-bar.

The operation of the device is as follows: The bolt N is detachable from the cross-frame H, and the legs I are also removable from the 45 clamp below. Fig. 1 represents the device as it has been placed on the wheel, the clamps C C' being loose on the spoke. To adjust it for operation the screw N is turned up to the position indicated by the dotted lines, and the 50 cross-frame H carrying the legs I, and also the clamps C C', raised to the position shown by the dotted lines, when the nut on bolt E is tightened, causing the clamps C C' to bind on the spoke. Thus the cross-frame H is elevated 55 above the felly and the hooks M rest against the under side of the felly. The bolt N is now screwed downward by means of a wrench on the head O, thus forcing the spoke downward and simultaneously raising the felly, when a 60 washer is placed between the end of the spoke and the felly to compensate for the wear of the wheel.

Having described my invention I claim—
In a spoke and tire tightener, the adjustable 65 clamp C C', in the upper side of which are loosely socketed the legs I I, projecting downward from the frame H over the felly, in combination with the threaded bolt N, passing centrally through a cross-bar, J, and socketed in the cross-frame 70 H, and carrying at each end a screw-threaded arm, K, having at the lower end a hook, M, to be placed under the felly, substantially as and for the purpose herein set forth.

JOHN THOMAS MCENNANEY.
